WILLIAM A. EDWARDS, OF CHICAGO, ILLINOIS.

TWO-CYCLE ENGINE.

1,353,465.

Specification of Letters Patent. Patented Sept. 21, 1920.

Application filed July 8, 1916. Serial No. 108,103.

To all whom it may concern:

Be it known that I, WILLIAM A. EDWARDS, a subject of the King of Great Britain, residing at Chicago, in the county of Cook and 5 State of Illinois, have invented certain new and useful Improvements in Two-Cycle Engines, of which the following is a specification.

This invention relates in general to gas 10 engines and has more particular reference to the two-cycle type, the aim of the invention being to improve the construction and increase the efficiency of this type of engine.

One of the objections heretofore inherent 15 in two-cycle engines is the difficulty of properly scavenging the cylinders, or, in other words, getting rid of substantially all of the burnt gases without permitting any of the explosive charge to escape through the 20 exhaust port. Engines of this character now in use customarily have the inlet port to the cylinder and the outlet port located on opposite sides of the cylinder, and the upper face of the piston is provided with 25 an upwardly extending deflecting portion designed to deflect the incoming gases upwardly away from the exhaust port with a view of having the burnt gases escape through the port before the incoming gases 30 approach this port in their travel within the cylinder. Experimentation, however, has conclusively proven that the deflector carried by the piston sets up such eddies and counter-currents in the incoming gases in 35 the cylinder that these gases instead of driving out the burnt gases ahead of them mingle with the burnt gases with the result that a portion of the explosive charge is discharged with the burnt gases through the exhaust 40 port and a considerable proportion of burnt gases, because of their mingling with the incoming gases, remain in the cylinder. This mingling of the incoming and burnt 45 gases obviously materially decreases the efficient working of the engine.

My present invention contemplates delivering the explosive charge to the cylinder in such a manner that it will circulate within the cylinder in a predetermined path and 50 drive the exhaust gases out ahead of it without any appreciable mingling between the explosive and burnt gases, with the result that practically all of the explosive charge

is retained, thus filling the cylinder with a pure explosive mixture which results in a 55 very high working efficiency.

It is customary, as is well known, in engines of this type to admit the explosive mixture from the carburetor into the closed crank case communicating with the lower 60 end of the cylinder beneath the piston, the gas being drawn into the crank chamber upon the upstroke of the piston and being compressed in the crank chamber to about ten pounds (10 lbs.) pressure upon 65 the downstroke of the piston. The explosive charge under this slight pressure is then admitted to the cylinder above the piston through a passage communicating at its lower end with the lower portion of the 70 crank chamber. I have found that the explosive charge entering the crank chamber from the carburetor is composed of a mixture of gases, vapors and particles of liquid gasolene carried in suspension, these gases, 75 vapors and liquids being of various specific gravities, and since the charge has heretofore been delivered from the upper portion of the crank case to the cylinder it is obvious that the lighter portions of the contents of 80 the crank case are delivered to the cylinder while the heavier portions gradually settle in the bottom of the crank case until a considerable quantity is accumulated. The action of the crank arm in the case, when a sufficient quantity of this heavy, rich mixture has 85 accumulated, will carry a portion of it into the upper part of the crank case from which it will be drawn as a slug of heavy, rich mixture into the cylinder. This slug is entirely too rich for proper explosive action, and the result is that an imperfect explosion occurs which causes uneven running of the engine. The more frequently these heavy, 90 rich slugs are delivered to the cylinder the more uneven will be the operation of the motor, and even under the most favorable conditions it is a well known fact that a two-cycle engine will periodically have one or more imperfect explosions which detract 95 from the rhythmic, even and efficient operation of the engine.

My present invention is designed to obviate this uneven running of a two-cycle engine and to deliver to the cylinder a continuous mixture of even and uniform rich-

ness. In order to accomplish this result instead of drawing the explosive charge from the upper portion of the crank case I propose to take it from the lowest point in the 5 crank case, so that the heavy, rich portions of the charge, instead of accumulating in the crank case and being fed to the cylinder at irregular periods and in large slugs, are continuously drawn from the crank case together with the other lighter portions of the 10 mixture and are delivered to the cylinder at each reciprocation of the piston, with the result that the explosive charge delivered to the cylinder is always of an even and uniform richness, which insures steady, uniform, even and efficient operation of the 15 motor.

In order to facilitate an understanding of my invention I have illustrated on the accompanying drawings one practical and preferred embodiment thereof from an inspection of which, when considered in connection with the following description, my invention and many of its attendant advantages should be readily appreciated. Referring to the drawings,

Figure 1 is a vertical sectional view through one cylinder of a two-cycle engine embodying my invention, the piston being 30 shown in its uppermost position; and

Fig. 2 is a similar view showing the piston in its lowermost position.

On the drawings reference character 3 indicates generally the cylinder walls of a two-cycle engine provided with the usual water jacket 4. The top or cylinder cap 5 may be of any preferred construction and is preferably equipped with the water cooling chambers 6 and the customary tapped opening 7 for a spark plug, this cap being secured in 40 position by the usual studs or stay bolts 8. The crank case, designated generally by reference character 9, is of the closed type, as shown, and communicates with the lower 45 end of the cylinder, the crank case and cylinder being coupled up as shortly as possible while still permitting sufficient clearance for the operation of the connecting link or piston rod.

50 The piston 11 is of the construction commonly employed in a four-cycle engine, the upper face of the piston being horizontal, as shown, and devoid of any deflectors or other gas-diverting devices heretofore attached to

65 pistons employed in two-cycle engines. The piston is connected in the usual manner by means of a link or piston rod 12 with the crank shaft 13 suitably mounted in bearings, not shown, and equipped with the usual fly-wheel 14.

60 The explosive mixture is supplied from a carbureter (not shown) to the crank case and the cylinder beneath the piston through a laterally opening port 15, this port being 65 opened and closed by the piston and so lo-

cated that it will be fully opened when the piston is at the upper end of its stroke, as shown in Fig. 1, and will be entirely closed when the piston has completed a limited portion of its downward stroke. A partial 70 vacuum will be created in the crank chamber, as is well understood, by the piston on its upward stroke and as soon as the port 15 is opened the explosive mixture will rush in and fill the crank chamber and the lower 75 portion of the cylinder so that when the piston is moved downwardly the mixture trapped in the crank case when the port 15 is closed will be compressed to about ten pounds (10 lbs.) pressure in the usual manner.

The charge in the crank case instead of being delivered to the upper portion of the cylinder around the piston from the upper portion of the crank case so that only the 80 lighter portions of the mixture are normally delivered to the cylinder, as has been previously explained, is delivered from the crank chamber through a passage 16 which communicates with the crank chamber at its 85 bottom or lowest point thereof, as indicated by reference character 17. The heavy portions of the mixture which have a tendency to settle to the bottom of the crank chamber are, accordingly, delivered through the passage 16 at each reciprocation of the piston and are discharged into the cylinder above the piston through the inlet port 18. It will be observed from Fig. 2 that the inlet port is fully opened when the piston has 90 reached the downward limit of its stroke, and the explosive gases are thereupon admitted under pressure and travel directly across the cylinder in a slightly upward direction due to the inclined position of the 95 upper end of the passage 16 until they strike the opposite wall by which they are deflected upwardly and then laterally by the cylinder cap and finally downwardly along the wall through which they first entered, 100 thus making a complete circuit of the cylinder chamber, driving the exhaust gases before them out through the exhaust port 19 which is located directly above and in alignment longitudinally of the cylinder with the 105 inlet port 18. From the exhaust port the 110 burnt gases are discharged through the usual exhaust pipe 21.

Exhaustive tests have thoroughly demonstrated that by locating both the inlet and 115 exhaust ports on the same side of the cylinder in proximity to each other with the exhaust port above the inlet port and in alignment therewith longitudinally of the cylinder the exhaust gases are driven out by the 120 incoming gases which travel in a clearly defined circuit through the cylinder chamber, and the cylinder is thoroughly scavenged and freed from the burnt gases so that practically a pure charge of explosive mixture 125 130

is left in the cylinder for effective working purposes. The relative location of the inlet and exhaust ports causes the exhaust port to be opened first and closed last by the piston so that sufficient time is afforded for the escape of the exhaust gases while a lesser but sufficient time is afforded for the incoming gases which are admitted under pressure, to completely charge the cylinder.

10 It will be manifest from the foregoing that I have provided an engine which is highly efficient in operation, since it delivers a uniform mixture at all times to the cylinder without any intermittent slugs of 15 extremely rich mixture which have heretofore been characteristic of two-cycle engines, and that by my peculiar arrangement of the inlet and outlet ports and as the result of the inclined position of the upper end of 20 the passage 16 I am enabled to thoroughly scavenge the cylinder of the burnt gases and to completely charge the cylinder with an explosive mixture undiluted or diminished in quality by the burnt gases. Furthermore, 25 it should be noted that my engine is entirely devoid of valves and valve mechanisms, since all of the ports, both inlet and exhaust to the cylinder and the inlet to the crank chamber are automatically opened and closed in 30 predetermined timed relation by the piston itself. It should be obvious therefore that my invention is not only highly efficient in operation but the engine is extremely simple in construction and can be manufactured at 35 relatively low cost. While I have illustrated and described one preferred embodiment of my invention it should be understood that the structural details disclosed are capable of considerable modification and 40 variation as to the size, shape, proportion and arrangement of the various parts without departing from the essence of the invention as defined in the following claims.

I claim:

45 1. A two-cycle engine, comprising a cylinder provided with inlet and exhaust ports, a piston devoid of gas deflecting provisions on its upper face arranged to reciprocate in said cylinder so as to open and close said 50 ports, a crank case, and means including a passage having an upwardly inclined delivery end for delivering an explosive charge from said crank case through said inlet port directly against the opposite side 55 wall of the cylinder and in an upwardly inclined direction below the longitudinal center of said cylinder.

60 2. A two-cycle engine, comprising a cylinder provided with an inlet and an exhaust port disposed in alignment longitudinally of the cylinder on one side thereof and having an inwardly convex cylinder head, and means for delivering an explosive charge

through said inlet port against the opposite side wall of the cylinder between the plane 65 of said port and the longitudinal center of said cylinder at an angle to the axis of the cylinder.

3. A two-cycle engine, comprising a cylinder having an inwardly convey cylinder head, a crank case, and means for delivering an explosive charge from said crank case into said cylinder at an angle to the longitudinal and transverse axes thereof so that the charge is projected against the opposite 75 cylinder wall above the port and below the longitudinal center of the cylinder, said cylinder being provided with an exhaust port adjacent to the point of admission of 80 said charge.

4. A two-cycle engine, comprising a cylinder, a crank case connected thereto, a flat topped piston reciprocable in said cylinder, said cylinder being provided with an admission port controlled by said piston so as 85 to admit gas to the crank case when the piston is in uppermost position and also provided with intake and exhaust ports located at one side of the cylinder in alignment longitudinally of the cylinder and 90 controlled by said piston so as to be opened when the piston is in lowermost position, and a passage leading from the lowest point of the crank case to said inlet port.

5. A two-cycle engine comprising a cylinder, a piston therein, a closed crank case communicating with said cylinder below said piston, means for supplying an explosive charge to said crank case, and means for conducting said charge from the lowest 100 point of the crank case to said cylinder above the piston.

6. A two-cycle engine comprising a cylinder communicating at its lower end with a closed crank case, a piston in said cylinder, a gas supplying passage opening into said cylinder through which an explosive charge is supplied to the crank case, said passage being arranged to be opened when the piston reaches the upper limit of its 105 travel, and a passage for conducting said explosive charge from the lowest point of said crank case to the explosion chamber of the cylinder, said passage being adapted to communicate with the explosion chamber when said piston is at the lower limit 110 of its travel.

7. A two-cycle engine, comprising a cylinder, a substantially flat-topped piston arranged to reciprocate therein, a crank case, 120 means for admitting fuel to said crank case upon the up-stroke of said piston, and means outside the cylinder chamber for delivering an explosive charge from the crank case through one of the side walls of said cylinder in an upwardly inclined direction di- 125

rectly against the opposite side wall of the cylinder remote from the top thereof so that said charge is caused to follow the contour of the cylinder and drive out the exhaust gases therefrom.

8. A two-cycle engine comprising a cylinder provided with exhaust and inlet ports; a flat-topped piston therein, a crank case, and a passage connecting the crank case

with said cylinder inlet port, said passage 10 and inlet port being upwardly inclined near their delivery end to deliver the explosive charge into said cylinder in an upwardly inclined direction directly against and below the center of the opposite side wall of 15 said cylinder.
